CEMENTING PLUG

Erd V. Crowell, Los Angeles, Calif.

Original application July 26, 1927, Serial No. 208,539. Divided and this application December 19, 1928. Serial No. 327,081

10 Claims. (Cl. 166—1)

This invention relates to cementing plugs adapted for use in cementing oil wells and the like, the present application being a division of my copending application Ser. No. 208,539, filed 5 July 26, 1927, which has issued as U. S. Patent No. 1,828,099, granted October 20, 1931.

It is an object of the invention to provide a plug adapted for convenient insertion and subsequent withdrawal from a usual string of well 10 casing so as to again present an unobstructed casing bore after a cementing operation.

It is a further object of the invention to provide a plug which will normally completely close the bore of the well casing but which is adapted 15 to be readily opened for drainage therethrough when the plug is subsequently withdrawn from the casing.

Further objects of the invention will be readily understood from the following description of the 20 accompanying drawing, in which:

Fig. 1 is an axial section through a string of well casing, showing the improved plug being lowered to operative position.

Fig. 2 is a similar view showing the plug in 25 operative position.

Fig. 3 is a similar view showing the method of withdrawing the plug.

Fig. 4 is a transverse section on the line 4—4 of Fig. 2.

For purpose of illustration the improved plug is described in connection with a cementing apparatus which includes a fixed section 1 of a string of casing A which is adapted for reception in well bore B. The section 1 is placed in the 35 string of casing at any predetermined level and preferably has a bore of slightly greater diameter than the remainder of the string; and at its lower end the section 1 may be connected to the string by a coupling 2 forming an internal supporting shoulder 3. Medially of its length the bore of the fixed section preferably forms an undercut shoulder 4, and ports 5 open through the wall of the fixed section just below this undercut shoulder. The ports 5 are normally closed by a 40 sleeve valve 6 slidable in the lower end of the bore of section 1 with the bore of the sleeve valve forming a uniform continuation of the bore of the string of casing; and the sleeve valve is yieldably shifted upwardly to close the ports and abut 45 against shoulder 4 by means of a coil spring 7 upon which the sleeve valve rests and which is in turn supported upon shoulder 3.

The spring 7 retains the sleeve valve in elevated, closed position irrespective of pressure in 50 the string of casing, but the sleeve is adapted to

be lowered against the tension of its spring so as to open ports 5, by means of an actuating plug which is lowered in the string of casing so as to engage by resting upon and depress sleeve 6 and then anchor on the sleeve with the ports open. 60

The actuating plug when thus anchored opens the ports and then closes the bore of the casing just below the open ports 5, and as a consequence a cementing mixture introduced into the string of casing in back of the anchored plug is prevented 65 from flowing downwardly through the casing past the plug and is discharged through open ports 5 into the surrounding well bore. A predetermined quantity of the cementing mixture is preferably thus discharged through the open 70 ports, the quantity of cement being measured by a traveling plug lowered in the casing in back of the cement, and in order to prevent leakage past either the actuating plug or the traveling plug they are preferably each provided with suitable 75 packing shown at 8 whereby they form a fluid-tight but sliding fit in the well casing.

The plugs are adapted to be removed subsequent to the cementing operation so as to again provide an unobstructed casing bore, and for 80 this purpose both the actuating plug 9 and the traveling plug 10 may be recovered from the well by use of a suitable tool; and the plugs are preferably provided with normally closed valves which are adapted to open when the plugs are 85 withdrawn so as to allow any fluid above the plugs to pass therethrough and thus eliminate all swabbing action.

As an instance of this arrangement the plugs 9—10 have open bores 11 provided with valve 90 seats 12 at their lower ends, and valves 13 are adapted to normally engage the valve seats for closing the bores of the plugs. The valves are retained in closed position by pressure above the plugs as they are lowered in the well casing, but 95 when the plugs are withdrawn the valves are lifted to open position by operatively engaging their valve stems 14. The valve stems are hollow tubing extending upwardly from the valves and sliding in guides 15 at the upper ends of the 100 hollow bores of the plugs, and these stems are adapted for engagement by a usual tubing spear C as shown in Fig. 3 when the plugs are to be withdrawn, so that elevation of the valve stems will first open valves 13 and then withdraw the 105 plugs by engagement of depending abutments 16 of the valves against the undersides of valve seats 12.

The actuating plug 9 may be provided with peripheral abutment slips which are adapted to 110

automatically expand when the plug has been lowered into the slightly enlarged bore of section 1 in order that said slips may rest against sleeve valve 6 for depressing the same to open ports 5 and then anchor the plug on the sleeve for closing the bore of the casing. These abutment slips are shown in Figs. 2 and 4 as a pair of arcuate slips 17 which are adapted to contract on plug 9 as the plug is lowered through the string of casing, and springs 19 are positioned in back of the slips so as to yieldably urge the same to expanded position where they will operatively engage sleeve valve 6.

In addition to the positive closure means for ports 5 which is formed by the sleeve valve 6 opening only through engagement by the actuating plug, the ports may be provided with auxiliary closure means at the exterior of section 1 of the casing, the said auxiliary closure means being adapted to open by pressure of material discharged outwardly through ports 5 when sleeve valve 6 has been opened, but automatically closing against back flow of material through the ports and into the casing irrespective of the position of valve 6. The auxiliary closure means are shown as spring strips 25 fixed at one end to the exterior surface of casing section 1, with the opposite swinging ends of the strips overlying and normally closing ports 5. Pressure of material discharged outwardly through the ports is thus adapted to swing the strips outwardly as shown in Fig. 2 for opening the ports, but as soon as all the material has been discharged through the ports the resiliency of the spring strips again closes the same to prevent back flow into the casing.

In operation the plug 9 is adapted to be lowered in the well casing as shown in Fig. 1, and when the plug reaches the valve sleeve 6 it rests upon and depresses the same to open ports 5, and by anchoring on the depressed sleeve valve it then closes the bore of the casing below the open ports, the parts in this position being shown in Fig. 2. The cementing mixture follows plug 9 into the casing, the quantity of cement being measured by lowering the traveling plug in back of the same, and the traveling plug is forced downwardly in suitable manner so that the cement flows outwardly through the open ports, the auxiliary valves 25 readily opening by the pressure of the flow for discharge of the cement into the surrounding well bore. The cement having been discharged the valves 25 automatically close to prevent back flow into the casing, and the plugs may then be immediately removed as previously described while the cement is yet plastic, whereupon the valve 6 will again close and the string of casing will thus provide a usual cemented well structure with the bore of the casing unobstructed and the ports in its wall positively held in closed position irrespective of pressure in the casing.

During said withdrawal of the plugs 9-10 their valves 13 will be shifted from normal closed position to open position as shown in Fig. 3, and the plugs thus normally present barriers for the entire cross-sectional area of the casing, but are adapted for ready engagement and withdrawal, and provide open passageways through the plugs during said withdrawal so as to permit free drainage of fluid.

I claim:

1. A plug adapted to be lowered in well casing and snugly engage the wall of the bore of the casing for confining material which is adapted

for discharge into the surrounding well bore, said plug having a bore, and a valve normally closing said bore and adapted for engagement by a tool to open the valve and withdraw the plug from the well casing. 80

2. A cementing plug adapted to snugly engage the wall of a bore and having an axial bore opening through the plug, and a valve normally closing the bore of the plug and adapted for engagement by a tool to open the valve and withdraw the plug. 85

3. A plug adapted to be lowered in a well, the plug having a bore, a valve seat at the lower end of said bore, a valve normally engaging the seat for closing the bore, and a hollow valve stem projecting upwardly from the valve and slidably in the bore, said hollow valve stem being adapted for engagement by a tool for opening the valve and withdrawing the plug from the well. 90

4. A plug adapted to be lowered in a well, the plug having a bore, a valve seat at the lower end of said bore, a valve normally engaging the seat for closing the bore against downward flow, a valve stem projecting upwardly from the valve and slidably in the bore, and a guide for the valve stem spaced from the wall of the bore so as to leave a passageway through said bore. 95

5. A plug adapted to be lowered in a well so as to snugly engage the wall of the well, means on the plug for anchoring said plug in the well, the plug having a bore, a valve normally closing said bore, and means for opening said valve and withdrawing the anchored plug from the well. 100

6. A plug carrying means slidably fitting a well casing and adapted to be forced by fluid pressure downwardly therethrough to actuate valvular means controlling ports in said casing, said plug carrying means cooperating with means attached to said casing to anchor said plug at a predetermined point therein, said plug having a bore, a valve normally closing said bore against downward flow, and means for opening said valve. 110

7. A plug carrying means snugly engaging the bore of a well casing and adapted to be forced by fluid pressure downwardly therethrough, means in said well casing cooperating with means on said plug to anchor the latter at a predetermined point within said well casing so as to close off the bore of said well casing therebelow, a bore in said plug, a valve normally closing said bore against downward flow, and an operating connection for opening the valve while the plug is anchored in the well. 120

8. A plug carrying means forming a fluid-tight sliding engagement with the bore of a well casing and adapted to be forced downwardly through said casing by fluid under pressure, means on said plug cooperating with means in said casing for arresting the downward movement of said plug at a predetermined point within said casing, a bore in said plug, a valve normally closing said bore against downward flow, and means carried by said valve for opening the same and facilitating the withdrawal of said plug from said well casing. 130

9. A barrier for mud fluid and cementing mixture adapted to be forced downwardly through a well casing by fluid under pressure and in its downward course to force the fluid before it into the space outside of the casing, said barrier carrying means cooperating with means within said casing to arrest its downward movement at a predetermined point within said casing so as to close off the bore therebelow, a bore in said barrier, a valve normally maintaining closure of 145

said bore, and means for opening said valve and facilitating removal of said barrier from said casing.

10. A barrier for mud fluid and cementing mixture carrying means forming a fluid-tight but sliding engagement with the bore of a well casing and adapted to be forced downwardly therethrough by fluid under pressure to force the fluid below it into the space outside of the casing, said barrier carrying means to open valves control-

ling ports in said casing and also carrying means cooperating with means within said casing to arrest the downward movement of said barrier at a predetermined point within said casing so as to close off the bore therebelow, a bore in said barrier, a valve normally maintaining closure of said bore, and means for opening said valve and removing said barrier from said casing.
